TWO-PIECE SELF-CLOSING CLOSURE
DEVICE

Robert Nyden, Manhasset, N. Y.

Continuation of application Serial No. 308,900,
December 13, 1939. This application July 21,
1942, Serial No. 451,740

14 Claims. (Cl. 222—498)

1

This invention relates to closure devices of the dispensing type for containers and particularly to devices that are capable of self-closing when released of the force for opening the same in dispensing small quantities of the contents of a container of which the device is a complementary part, and is a continuation of my co-pending application Serial No. 308,900 filed December 13, 1939.

It is the principal object of this invention to provide a two-piece self-closing closure device in which one member on being manually moved relative to the other member for opening the device will create a component of forces inherent within the two members, which forces will be sufficient to automatically return the movable member to closed position when released of the opening force.

A further object is to provide a closure device of the above nature including an outlet or head member having a discharge orifice and a generally rounded closed end and a lid or closure member pivotally engaged to the side walls of said outlet member and designed to operate over said rounded end in moving between open and closed positions, the construction and the arrangement of the members being such that the closure member coacts with said outlet member upon opening movement to create a progressively increasing tensioning stress between said members of a force sufficient to automatically close the closure member when released of the opening force.

Another object is to provide a closure device in accordance with the above general construction in which the closure member is pivotally engaged to the side portion of the outlet or head member in such a manner that in normal closed position a portion of the closure member is stressed to create a constant tensioning effect for the purpose of yieldingly retaining the closure member in closed position and also effect a tight seal over the discharge orifice, and further which tensioning effect is conducive in effecting a wiping action throughout the entire closing stroke of the closure member to clean off any excessive material lodged about the discharge orifice.

Other objects and advantages of the invention will hereinafter appear.

In the drawings accompanying and forming a part of this application,

Fig. 1 is a side elevation of a container having attached thereto my improved dispensing device compressing an outlet member and an

2

outlet closure means applied thereto and showing the latter in outlet-closed position.

Fig. 2 is a view looking at the left of the upper portion of Fig. 1 and showing the outlet closure means in outlet-open position.

Fig. 3 is a view looking at the right of the upper portion of Fig. 1.

Fig. 4 is a sectional view on an enlarged scale taken on the line 4—4 of Fig. 3 and showing the outlet closure member in outlet-closed position.

Fig. 5 is a view taken on the line 5—5 of Fig. 2 showing the outlet closure member in outlet-open position.

Fig. 6 is a view looking at the top of the container and showing the outlet closure member in outlet-open position.

Fig. 7 is a perspective view of the outlet closure member.

Fig. 8 is a view similar to Fig. 1 showing a container provided with a modified embodiment of the dispensing device comprising the outlet member and outlet closure member and showing the latter in outlet-closed position.

Fig. 9 is a view looking at the left of the upper portion of Fig. 8 but with the closure member in outlet-open position.

Fig. 10 is a view looking at the right of the upper portion of Fig. 8.

Fig. 11 is a sectional view on an enlarged scale taken on the line 11—11 of Fig. 10.

Fig. 12 is a sectional view on an enlarged scale taken on the line 12—12 of Fig. 9.

Fig. 13 is a view looking at the top of the container and showing the outlet closure member in outlet-open position; and

Fig. 14 is a perspective view of the outlet closure member, per se, shown in Figs. 8 to 13, inclusive.

In carrying out the embodiment of the invention shown in Figs. 1 to 7, inclusive, there is provided a head or outlet member in the form of a hollow sheet metal shell or body secured at its open end by a flanged portion 15 to the wall surrounding an opening in the crown portion of a cover B such as used for closing the open end of containers generally indicated by letter A. While the outlet member is shown as constructed independently of and secured to the cover of a container, it may be constructed integral with an end of the container or the cover.

The end or upper wall portion of the outlet member is formed into an exterior arcuate or convex surface 16 arranged in an arc of a circle whose center lies in the longitudinal or vertical center of the outlet member, said surface inter-

secting and equal portions thereof disposed at opposite sides of said longitudinal center. An outlet orifice 17 opens through the convex surface 16 to one side of said center of the outlet member, said orifice being of less width than said surface 16, as shown in Fig. 6. The convex end surface 16 merges at its opposite ends as indicated at 16' with wall portions having an exterior arcuate or convex surfaces 18 arranged in arcs of circles having a longer radius than the convex surface 16 and whose centers coincide and also lie in the longitudinal or vertical center of the outlet member, and said surfaces 18 merging with opposed parallel exterior surfaces 19 extending perpendicularly to the securing flange 15. The wall surfaces 16, 18 and 19 are of a width less than the space between parallelly extending portions 20 of the side walls, and merge therewith by a bevelled or inclined portion 20', as shown in Figs. 2, 3, and 6.

The closure member comprises a lid or cover of resilient material having a portion 21 formed at one end in a true arc of a circle, arranged concentrically of the convex surface 16 of the outlet member and serving to cover the general area of the convex surface 16 on the side of the outlet orifice 17. The true arcuate portion 21 merges into an arcuate portion 22 which is a developed surface not conforming to a true arc of a circle and arranged to be gradually relieved from the convex surface 16 (see Fig. 4) as it extends thereover in an eccentric manner. The developed portion 22 in turn merges with a portion 23 extending in a plane substantially tangential to said developed portion 22, but with an inwardly depressed or reentrant angular section 23' disposed therebetween. The crown end of the interior surface of the angular section 23' lies in a cylindrical plane common to the interior surface of the arcuate portions 21 of the closure lid, if theoretically extended to that portion, for purposes hereinafter described. The lower extremity of the portion 23 is flanged outwardly to provide a finger engaging member 24, by means of which the device is manually operated.

The closure lid is mounted on the outlet or head member to have pivotal movement on a transverse axis coincident with the center from which the convex surfaces 18 of the closure lid are struck. For this purpose the closure lid is arranged with arms 25, preferably constructed integrally therewith, extending radially inward from opposite sides of the end portion 23, and said arms are pivotally mounted on the opposite side walls 20 of the outlet member on an axis coincident with the center of the convex surfaces 18. The pivot connections are provided by depressing the material of the free end of the arms 25 inwardly to produce opposed trunnions 26 which are adapted to be removably snapped and to pivotally engage in complementary recesses or sockets 26' formed in the side walls 20 of the head member, as shown in Figs. 4 and 5. The portion 23 and integral arms 25 are reinforced by stamping a longitudinal rib 27 outwardly at an intermediate portion thereof, as best shown in Fig. 7.

The fact that the rib 27 extends longitudinally through the portion 23 and the finger engaging member 24 is formed angularly outwardly from its longer edge strengthens said portion 23 against any tendency to bend, and further the fact that the rib 27 is co-extensive with portions of the legs 25 stiffens the legs and gives to them a higher degree of resiliency so as to preclude

their trunnions 26 becoming easily disengaged from their respective sockets 26'.

The closure lid in its normal state when removed from the outlet head is constructed so that the distance between the axis of the arm trunnions 26 and the inner surface of the portion 23 is substantially equal to the radius of the convex surfaces 18, and the distance between the trunnions 26 and the inner surface of the arcuate portion 21 is substantially less than the distance between the axis of the pivot sockets 26' and the convex surface 16 of the outlet head. By this arrangement, when the closure lid is assembled upon the outlet head as shown in Figs. 1 and 4 with the arcuate portion 21 covering the outlet orifice 17 and the trunnions 26 engaging in sockets 26', the arcuate portions 21 and 22 are consequently forced or sprung out from their normal set position relative to the closure lid with the crown surface of the angular section 23' engaging the surface 16 and serving more or less as a fulcrum point. Thus it will be evident that the portion 21 will constantly be disposed under a resilient tension to yieldingly urge the same into engagement with the convex surface 16 for the purpose of affording a good seal for the outlet orifice and also maintaining the closure lid in a firmly closed state when not in use. It will be further apparent from the above arrangement that during opening movement of the closure lid, the free end portion 21 tends to move in an arc of a circle having a longer radius than the radius of the convex surface 16, but due to the fact that the portion 21 is forced to ride or cam over said surface 16 the closure member is further subjected to a progressively increasing tensioning stress which is additive to the force affected by the assembly of said members, and the co-action between which members create a component of forces reacting to automatically return the closure member to normal closed position when released of the opening force.

To actuate the closure member or lid to outlet orifice opening position, manual pressure is applied to the outwardly extending flange 24 moving the closure lid in a clock-wise direction as viewed in Figs. 1, 4 and 5 to full open position with said flange 24 engaging attaching flange 15 as a stop and thereby uncovering the arcuate portion 21 from the outlet orifice 17, it being necessary to hold the lid open against the opposing forces inherent within the lid during the time required to dispense the desired amount of the container contents through the orifice 17. When manual pressure is released from the operating flange 24 the closure lid will, of course, return in counter-clockwise direction to closed position, and said lid is limited in return movement by the crown surface of the angular section 23' abutting against the adjacent portion of the convex surface 16 as a positive stop. It will be further apparent from Fig. 5 that the relative position of the closure lid convex portion 21 to the convex surface 16 of the head during closing movement is such that the free end thereof is yieldingly urged into engagement with the said surface 16 and scrapes off therefrom any material which may adhere thereto around the outlet orifice 17.

The embodiment of the invention illustrated in Figs. 8 to 14, inclusive, functions in the same manner as the embodiment of Figs. 1 to 7, inclusive, in that the outlet member and closure member or lid are arranged to cooperate with each other during opening movement to exert a progressively increasing tensioning stress on the

closure lid and a resultant component of forces that serves to return the lid to normal closed position when relieved of the force for opening the same, and said lid is also stressed to constantly retain said lid in closed position against an accidental opening force and assure a good seal for the outlet orifice.

The outlet or head member comprises a sheet metal shell formed with free marginal portions flanged outwardly and arranged in circular form and secured to the wall bounding an opening in a container or a cover therefor by clamping the flange thereto, the same as in the arrangement of Figs. 1 to 7, as shown at 15.

The exterior surface 29 of the upper portion of the head member is of arcuate or convex form arranged in an arc of a circle the center of which lies in the longitudinal or vertical center of the head member with portions of said surface disposed at opposite sides thereof. One end of said arcuate surface 29, the end at the left as shown in Figs. 11 and 12, merges with an inwardly arcuate or concave surface 30 having an outlet orifice 31 opening therethrough. The lower end of surface 30 in turn merges with a convex surface 29' arranged in an arc of a circle having the same radius as the convex surface 29. The convex surfaces 29, 29' extend to a point in line with the center from which said surfaces are struck and merge with surfaces 32 extending parallelly of the longitudinal center of the outlet member to the flange 15.

The closure member or lid is constructed of resilient material and has an arcuate or convex portion 33 normally arranged concentrically of the convex surface 29 of the outlet member. The portion 33 integrally connects with a concave portion or sealing plate 34 at one end of the closure lid conforming in shape to the concave surface 30 of the outlet member. The portion at the opposite end of the convex portion 33 is flanged outwardly and arranged as a finger or manual engaging member 35. The closure lid is mounted upon the outlet member to have pivotal movement on a transverse axis relative thereto for opening and closing the device. For this purpose arms 36 extend radially inward from the proximal end of the closure lid adjacent the flange 35 and pivotally engage on the opposite side walls 20 of the outlet member. The arms 36 are adapted to have pivotal movement on an axis coincident with the axis of the convex surface 29, and which pivots are provided by forming in the free ends of said arms 36 trunnions 37 adapted to engage in complementary recesses or sockets 37' depressed in the side walls 20 of the outlet member. The arms 36 and the portion of the closure lid from which they extend are provided with an outwardly stamped reinforcing rib 36'. Similar to the first form described, the wall surfaces 29, 30 and 32 of the outlet member preferably of less width than the distance between the side walls 20 and are joined thereto by the bevelled or inclined wall portions 20'.

In order to effect the self-closing feature for the closure lid and maintain the same in yieldingly firm closed position upon the outlet head, the lid is so constructed that in its normal state when removed from the outlet head the distance between the axis of the arm trunnions 37 and the inner surface of the sealing plate 34 is less than the distance between the axis of the side wall sockets 37' and the outer concave surface 30 of the outlet member. By this arrangement

when the outlet member and closure lid are assembled the latter is distorted out of its normal set position and consequently setting up stresses in the closure lid that serve to constantly urge the sealing plate 34 to seat in the concave surface 30 of the outlet member for sealing the outlet orifice 31.

In order to impart further tensioning stresses to the closure lid during its opening movement, a pair of opposed parallel guide ribs 38 are formed upwardly from the opposite edges of the arcuate surface 29, which ribs extend from the juncture of the surface 29 with the concave surface 30 a considerable distance over the face of surface 29 in the opposite direction. The ends of the ribs adjacent the concave surface 30 designated as 39 are substantially tangential to the surface at the juncture of the convex surface 29 with the concave surface 30, and said rib ends 39 act as cam surfaces in a manner as will appear later. The ribs 38 incidentally serve as guide means for the intermediate portion 33 of the closure lid when the latter is returning to normal closed position, and further said ribs 38 also serve to protect the closure lid should the container be accidentally dropped upon its head.

As best shown in Fig. 14 the sealing plate 34 is considerably wider than the intermediate portion 33 of the closure lid, thus providing projections that are adapted to ride over the cam ends 39 and upon the ribs 38 during the opening movement of the closure lid. (See Fig. 12.) Due to the relative differences in dimensions between the co-acting portions of the closure lid and outlet member, as explained above, it will be apparent that additional tensional stresses are exerted to the closure lid during its opening movement other than those previously mentioned, which stresses in combination with the cooperative relationship of the members result in creating a component of forces that operate to automatically return the closure lid to normal closed position when relieved from the manual opening force. The opening movement of the closure lid similar to the first form is limited by the manual engaging flange 35 engaging with the attaching flange 15 of the outlet member.

It will be apparent that both forms of this invention as here illustrated are characterized by locating the pivots on the shell or head member about which the lid member moves at a point closer to the outlet opening than it is to the portion of the surface engaged by the cover member when moved to expose the opening, but it is to be also understood that other arrangements might be resorted to wherein the crux of the invention resides particularly in providing a two-piece pivoting closure device in which the closure member is a sheet metal stamping made of resilient material having portions thereof stressed coincident with the opening movement due to cooperative engagement with the head member resulting in a force that will react to return the closure member to closed position.

This dispensing device as embodied in two forms is applicable for use in connection with containers for dispensing pulverulent materials, such as tooth powder, or talcum and dusting powders and when used for the latter purpose a series of perforations may be substituted for the outlet orifice, and further the device is also applicable for use with containers for dispensing semi-liquid substances, such as tooth paste and shaving cream.

I claim:

1. A container closure comprising a head shell provided with an outlet orifice and an outer arcuate surface extending above said orifice, a closure member of resilient material and having a portion conforming to said arcuate surface, arms extending radially inward from opposite side edges of said member and pivotally engaging on opposite sides of said shell, said pivotal engagement of the arms with the shell being positioned relative to said arcuate surface to tend to move the closure member during opening movement in an arc having a longer radius than said arcuate surface whereby the closure member is caused to cooperate with said arcuate surface and subject said closure member to a tensioning stress reacting to impart return movement to the closure member to its normal closed position.

2. A container closure comprising a head member provided with an outlet orifice and an outer arcuate surface, a closure member of resilient material and having a portion conforming to said arcuate surface, arms extending radially from said closure member and having pivotal engagement on opposite sides of said head member, the pivots of said arms being arranged relative to said arcuate surface such that upon application of an opening force said closure member will tend to move in an arc of a circle having a longer radius than the radius of said arcuate surface and to cooperate with said arcuate surface and be subjected to a progressively increasing tensioning stress reacting to move the closure member to closed position when released of said opening force and to yieldingly retain said closure member in closed position.

3. In a closure for containers, a head member having an arcuate closure seat with an outlet orifice therein, a closure member having an arcuate resilient portion conforming to said closure seat, arms extending from said closure member and having pivotal engagement with the side walls of said head member to permit relative movement of said closure member over said closure seat, said pivotal engagement of the closure member with the head member being arranged to cause cooperative action between the closure and head members whereby the resilient portion of said closure member during its opening movement is subjected to a tensioning stress thus creating a force sufficient to automatically move the closure member to normal closed position when released from the opening force.

4. In a closure for containers, a head member having an arcuate closure seat with an outlet orifice therein, a closure member having an arcuate resilient portion conforming to said closure seat, arms extending from said closure member and having pivotal engagement with the side walls of said head member to permit relative movement of said closure member over said closure seat, said pivotal engagement of the closure member with the head member being arranged to cause cooperative action between the closure and head members whereby the resilient portion of said closure member during its opening movement is subjected to a progressively increasing tensioning stress thus creating a force sufficient to automatically move the closure member to normal closed position when released from the opening force, and further means for maintaining said resilient portion of said closure member in a state of constant tension over said orifice during closed position.

5. In a closure for containers, a head member

having an outer arcuate surface and an outlet orifice therein, a closure member of resilient material and having an arcuate portion conforming to said arcuate surface and normally covering said outlet orifice, arms extending radially and parallelly from the opposite side edges at an end of said closure member and pivotally engaging opposite side wall portions of the head member to permit the arcuate portion of the closure member to move relative to said arcuate surface, the pivotal engagement of the arms of the closure member with the head member being arranged to cause the arcuate portion of the closure member to cooperate with the arcuate surface of the head member in such a manner as to subject the closure member during its opening movement to a tensioning stress acting to automatically move the closure member to closed position when released of the opening force, and means effecting a constant tensioning stress between the arcuate portion of the closure member and the arcuate surface over the outlet orifice during normal closed position.

6. In a closure for containers, a head member having an outer arcuate surface at the end the center of which lies in the longitudinal center of the head member and having an orifice therein at one side of the longitudinal center of the head member, a closure member of resilient material and arranged in an arc of a circle having a radius substantially equal to the radius of the arcuate end surface and having arms extending radially inward from the opposite side edges at one end thereof, said arms having pivot and socket connections with the opposite sides of said head member on an axis intersecting the longitudinal center of the head member and said arms extending radially to one side of said longitudinal center opposite the orifice, said closure member being of a length to extend from the arms to that side of the longitudinal center of the head member having the outlet orifice therein and adapted to be disposed on that side of the longitudinal center of the head member in all positions of said closure member, and said pivotal engagement of the arms with the head member being arranged to cause said closure member during opening movement to cam over said arcuate surface and subject said closure member to a tensioning stress in all positions resulting in a force reacting to move said closure member to closed position.

7. In a closure for containers, a head member provided with an outlet orifice and having a closure seat, a closure member having a resilient portion conforming to said closure seat and normally covering said orifice, arms extending from said closure member and having pivotal engagement with the sides of said head member to permit relative movement of said closure member over said closure seat, the pivot axis being arranged relative to said closure seat so that upon assembly of said closure member on said head member the resilient portion is flexed out of its normal set position to create a force constantly tending to retain said closure member in closed position and yieldingly urge said resilient portion against said closure seat over said orifice.

8. In a closure for containers, a head member having an arcuate closure seat with an outlet orifice therein, a closure member having a resilient portion conforming to said closure seat and extending from an integral reinforced portion at one end of said resilient portion, radial arms extending from opposite ends of said reinforced portion, the free ends of said arms having pivotal

engagement with the sides of said head member to permit relative movement of said closure member over said closure seat, the means for reinforcing said portion being co-extensive with a portion of said arms to give added strength and a higher degree of resiliency thereto and assure a better pivotal engagement between the arms and head member, the pivot axis being arranged relative to said closure seat such that upon the assembly of said closure member on said head member the resilient portion thereof is flexed out of its normal set position to create a force constantly tending to retain said closure member in closed position and yieldingly urge said resilient portion against said closure seat over said orifice.

9. A closure for containers as claimed in claim 8 wherein the closure member is provided with a reentrant angular section defining an inwardly disposed transverse rib positioned substantially at the juncture of said resilient portion and reinforced portion with its inner surface contacting said closure seat as a stop for the return movement of said closure member.

10. In a closure for containers, a head shell having a convex surface at the end intersecting the longitudinal center of the shell and a concave closure seat at one end of said convex surface having an outlet orifice therein, a closure member of resilient material and having an arcuate portion at one end conforming in shape to the concave closure seat of the shell and adapted to engage therewith to close the outlet orifice, said member having an arcuate portion extending from and curved reversely to said arcuate end portion and adapted to be disposed concentrically of the convex surface of the shell, arms extending inward from the opposite side edges of said closure member at the end opposite the arcuate outlet orifice closing portion for pivotally engaging opposite sides of the shell on an axis coincident with the center of the convex end surface of said shell, means on the closure member to permit manual opening operation, and further means on the shell engaged by the closure member during opening movement operative to subject the closure member to a tensioning stress creating a force capable of automatically moving said member to normal closed position when released of the opening force.

11. A container as claimed in claim 10 wherein the means on the shell engaged by the closure member in the outlet orifice opening movement thereof and operative to place the closure member under a tensioning stress, comprises guides at the opposite sides of and projecting from the convex face of the outlet member and having ends adjacent the concave surface of the shell that serve as cam surfaces over which said closure member is adapted to ride and effect a tensioning stress during the opening movement thereof.

12. A two-piece self-closing container closure

comprising a head member having a rounded end and a discharge orifice, a closure member conforming substantially to said rounded end and having a resilient portion for normally covering said discharge orifice, said closure member having pivotal engagement with the side walls of said head member for operating over said rounded end, and means inherent within the construction and relative arrangement of said members to produce upon the opening movement of said closure member a tensioning stress within its resilient portion of a force sufficient to automatically return said closure member to normal discharge orifice closing position when released from the opening force.

13. A two-piece self-closing container closure comprising a head member having a rounded end and a discharge opening on one side of said end, a closure member having a resilient portion for normally covering said discharge opening and conforming substantially to said rounded end, said closure member having pivotal engagement on an axis transverse to said head member and eccentric to said rounded end whereby opening movement of said closure member causes the resilient portion thereof to cam over said rounded end and be flexed out of its normal set position and create a force sufficient to automatically return said closure member to normal closed position when released from the opening force.

14. A self-closing discharge device comprising a shell with a discharge opening therein, a closure member having resilient means thereon engaging the shell and movable into and out of position to close said discharge opening, and pivot means connecting the closure member to said shell, the surface of said shell engaged by the resilient means on said closure member when said member is moved to expose said opening being spaced a greater distance from said pivot means than that portion of said shell adjacent said opening so that movement of the closure member to expose said opening serves to displace and stress said resilient means and cause said means to urge the closure member toward its closing position.
